COMBINED MEASURING CUP AND CLOSURE

Ned H. Neal and James C. Lower, Toledo, Ohio, assignors to Lehn & Fink Products Corporation, Bloomfield, N.J., a corporation of Delaware

Filed Apr. 2, 1963, Ser. No. 74,259

Term of patent 14 years

(Cl. D58—26)

FIGURE 1 is a top view of a combined measuring cup and closure showing our new design;

FIGURE 2 is a side elevational view thereof;

FIGURE 3 is a rear elevational view thereof;

FIGURE 4 is a front elevational view thereof;

FIGURE 5 is a bottom plan view thereof; and

FIGURE 6 is a sectional view thereof taken on line 6—6 of FIGURE 1, the portions shown in broken lines being for illustrative purposes only.

We claim:

The ornamental design for a combined measuring cup and closure, substantially as shown and described.
